UNITED STATES PATENT OFFICE.

WILLIAM F. LUM, OF WATERLOO, WISCONSIN.

IMPROVEMENT IN BAG-HOLDERS AND FILLERS.

Specification forming part of Letters Patent No. 121,529, dated December 5, 1871.

To all whom it may concern:

Be it known that I, WILLIAM F. LUM, of Waterloo, in the county of Jefferson, in the State of Wisconsin, have invented certain Improvements in Bag-Holders and Fillers, of which the following is a specification:

The object of this invention is to so construct a bag-filler that it can be used as a bag-holder, and receive the grain and conduct it into the bag; and it consists in the construction of the filler or shovel, that when it is placed upon a support it will hold the bag open to receive the grain that is to fill it, or, when desired, be used as a grain-shovel by which the grain is lifted and delivered into a bag.

In the drawing, Figure 1 is a side view of the holder and filler. Fig. 2 is a front view of the same. Fig. 3 is a side view of the filler; and Fig. 4 is a back view of the same.

A represents the frame of the support for the bag-holder in position, with a bag-holder and bag thereon. The frame A is made in two parts and hinged together by hinge a. A' is an adjusting-bar that is pivoted to one part, and has notches a² thereon, by which it is hooked onto a stud or knob, a¹, on the other part, and so as to spread the feet or bottom ends of the support further apart, or hold them when brought nearer together. a³ is an upright, broad piece, put between the transverse girts of the front part of frame A for the bag to rest against while being filled, as seen in Figs. 1 and 2. B is the bag-holder, as shown in Figs. 1 and 2, and is made of sheet metal, in the form shown, with a long staple, b¹, fast on and projecting from opposite edges thereof, which, when the holder is in position, as seen in said Figs. 1 and 2, rest in hooks a⁴ that project from the front of frame A, and keep the holder with the bag in position. b² is a band, oval in form, surrounding the lower or back end of the holder or filler, and is securely attached to the body of B, and when so secured has mortises b³ through it and the metal that forms the body of the holder or filler, and projecting from it are three or more hooks or ears, d, over which the hem of the bag is placed, and by which the bag is supported. B' is the head or back of the holder, also made from sheet metal, and curved back, as seen in Figs. 3 and 4, and has as many hooks upon it as there are mortises in and through bend b², so that

when it is necessary to use B as a shovel or scoop or filler the hooks b⁴ will go into mortises b³, and thus close up the back end to form a filler. b⁵ is a handle fast on the back side of B' to assist in handling when used as a filler. B'' is a bail-handle, attached to the body of B at the proper point for easy handling it when used as a shovel or scoop. C is the bag to be filled, attached to the band b² of the holder B by passing the bag around the holder and band, with the hem of the bag above the hooks or ears d, and drawn tight around the same and folded over in front, when the bent-spring e is forced over the folded bag and band, which holds it firmly in its place to be filled. e is a metal spring, bent into the form and used to hold the bag upon the band b², as seen in Fig. 1.

The holder B with the bag attached can be placed upon the supporting-hooks a⁴, as seen in Fig. 1, or if the bag is too long to be thus hung, the bottom of the projecting side staples may be placed in hooks a⁴, and thus hold a longer bag in proper position for filling. Any number of intermediate bars may be attached to the staples b¹ to accommodate the different lengths of bags, and have them at the proper height for successful filling. The bail-handle B'' can be removed from the scoop B when necessary, or when used as a bag-holder, as can also the head or back of the scoop when so used, as is seen in Fig. 2. The supporting frame A, by being constructed as shown and described, is capable of being folded together when not in use, by which means it will occupy but little space when it is desirable to store it away after being used. Constructing the scoop to be used as a bag-holder is believed to be novel and of great utility, as when not wanted as a bag-holder it is readily transformed into a scoop or shovel to handle or stir grain, as it will be found to be a handy tool for that purpose, the operator taking hold of handle b⁵ of the head B', when hooked in place within the band b², with one hand, and the other hold of the bail-handle B'', when it will be found that it is easier to lift and stir grain or fill it into a bag than by the use of an ordinary scoop-shovel, because you lift the grain directly, and without making one hand the fulcrum over which the grain is raised by bearing down upon the extreme end of a handle of such scoop or shovel.

Having thus described my invention, what I claim and desire to secure by Letters Patent, is—

1. The scoop B, having a removable head, B', and bail-hand B'', when the same is constructed and arranged to operate as described.
2. The scoop B, with side-staples b¹, and without the head B', in combination with the projecting hooks a⁴ and frame-support A, in the manner shown and described.
3. The open scoop B, as seen in Fig. 2, having

band b² surrounding it, with hooks or ears d thereon, in the manner and for the purpose described.

4. The open scoop B, having band b² with hooks d thereon, in combination with the bag C and spring-holder or fastener C, in the manner shown and described.

WM. F. LUM.
